CLAIM

The ornamental design for a color matching card, as shown and described.

DESCRIPTION

FIG. 1 is a top plan view of a color matching card showing my new design;

FIG. 2 is a side elevational view of the same; and

FIG. 3 is an end elevational view of the same;

An end elevational view taken of the end opposite that shown in FIG. 3 is identical thereto.

A side elevational view taken of the side opposite that shown in FIG. 2 is identical thereto.
